By his Attorneys
Hank Cuddy & Smith

UNITED STATES PATENT OFFICE.

ALAN W. C. MENZIES, OF PRINCETON, NEW JERSEY.

DEVICE FOR TREATING CIGARS, CIGARETTES, AND THE LIKE.

Application filed February 3, 1926. Serial No. 85,617.

My invention relates to a device for treating cigars, cigarettes, and the like. More particularly the invention relates to a device for introducing moisture into the body of 5 smokable rolls of material such for example as cigars, cigarettes, and the like.

Among the objects of the invention are:— to provide a device for treating smokable articles whereby a substantial amount of the 10 treating substance such as water may be readily applied to the interior of the body without unduly wetting the ends to apply moisture quickly just before smoking; and to provide a suitable device which is adapted 15 to efficiently carry out the results looked for and which will be inexpensive to construct and durable and easy to operate.

Further objects and advantages of the invention will fully appear from the following 20 description taken in connection with the accompanying drawings illustrating by way of example preferred embodiments of the device used in carrying out the results looked for.

25 The invention consists in the novel features, arrangements, construction and combination of the parts of the device, hereinafter described in accordance with certain preferred embodiments thereof, and the invention will be more particularly pointed 30 out in the appended claims. According to my invention I inject the treating substance, such as water, into the inner portion of the cigarette or the like; preferably applying it 35 at a region somewhat remote from the ends so that the interior of the cigarette, for a substantial length thereof, may be substantially moistened without unduly wetting the ends.

40 I have found out that by inserting a liquid, such as water, into the body of cigars, cigarettes, and the like, that certain beneficial results are obtained. For example, by injecting water into the body of a cigarette 45 or the like, preferably adjacent to but removed from the end to be inserted into the mouth of the smoker, I have found that the resulting product furnishes a cool and pleasant smoke. From experiments I have 50 discovered that cigarettes so treated may be smoked in larger quantities with less injurious results than when not so treated. This is probably due to the fact that the moisture

so applied tends to absorb volatile irritants, to cool the smoke and to humidify the gases 55 passing through the moistened region. A cigarette so treated has been found to furnish, in fact, a much milder smoke and to burn the tongue less than the same grade of cigarette not so treated. I have also found 60 that although the body of the cigarette is quite thoroughly moistened it seems to readily burn as it is smoked.

Referring to the drawings, which illustrate preferred embodiments of a device adapted 65 to be used in carrying out the method:—

Fig. 1 is a plan view, with parts broken away, showing one form of the device,

Fig. 2 is a similar view of another form of the device with a detachable end and a 70 hollow plunger provided with a closure means, and

Fig. 3 shows a modified form of the detachable end of Fig. 2.

Referring to the drawings, and more particularly to Fig. 1, the body of the device comprises a reservoir portion 1 which is cylindrical in form and a receptacle or tubular end portion 2 which is adapted to receive and to guide the end of a cigarette (indicated in outline as 10), and in the present embodiment is formed integral with the reservoir 1. The interior of the reservoir 1 is provided with screw threads 3 which are adapted to be engaged by corresponding threads formed on the piston or plunger 4. This plunger 4 in the present embodiment is provided with a plunger head 5 which is attached to the plunger by means of the screw 6; and the outer end of the plunger 4 is provided 85 with a knurled hand engaging portion 7. A plug 8 is inserted in the body and serves to separate the reservoir 1 from the receptacle end 2 and is attached in place by any suitable means such as by soldering. A hollow perforating member such as a needle 9 extends through the plug 8 to which it is attached and projects to a point adjacent the end of the tubular portion 2, which latter serves not only for guiding the end of the cigarette to be moistened, but protects the needle 9 when the device is carried about on the person. It will therefore be seen that a hollow needle 9 forms an outlet means from the reservoir 1, and that when the plunger 100 4 is rotated in a clockwise direction, it is

2
moved downwardly in the cylindrical reservoir 1 and serves to force the substance contained in the reservoir out through the hollow needle 9.

5 Referring to Fig. 2, in which the prime numerals have been applied to parts corresponding to the parts of Fig. 1 bearing the corresponding base numerals, the following modifications will be noted. The cylindrical reservoir 1' is threaded beyond the point where the plug 8' is inserted, and the plug 8' is threaded thereby permitting it to be screwed into position. The receptacle end 2' is provided with a reduced exterior diameter which is externally threaded, thereby permitting it to be screwed into the end of the cylinder 1', and this also serves to hold the plug 8' and the needle 9' carried thereby in place. In this modification the plunger 4' 10 is formed of a hollow tube exteriorly threaded to engage the interior threads of the cylinder 1'. The inner end of the plunger is provided with a plunger end 5' which is held in place by the pin 6'. The knurled 15 hand engaging end 7' is screw threaded on its inner end and adapted to engage interior threads provided in the plunger 4', thereby serving as a closure means for the hollow plunger. This hollow plunger provides a 20 storage space for cleaning rods which may be useful in clearing out the hollow needle 9'. The receptacle end 2', in this instance, is adapted to receive a cigarette, being formed in a manner similar to the end 2 of 25 Fig. 1.

Referring to Fig. 3, a receptacle end 2^a is shown which is adapted to replace the end 2' of Fig. 2. The end 2^a is adapted to receive a cigar.

40 *Operation.*

In treating the article to be smoked, one end of a cigarette or the like is inserted in the receptacle end 2 which guides the ends 45 so that the needle 9 perforates the end of the cigarette in substantial alignment with the longitudinal axis thereof and extends a suitable distance into the body of the same. The knurled handle 7 is then turned in order to 50 force the plunger 4 into the reservoir 1, which thereby forces the treating substance from the reservoir 1 through the needle 9 into the body of the cigarette 10. For example, in using water as a treating substance, a substantial amount of water is 55 forced into the body of the cigarette to substantially moisten a portion thereof. In practice I have found that the cigarette may be moistened from a point adjacent the end 60 to be lighted practically down to the end to be inserted in the smoker's mouth, without in any way affecting the burning of the cigarette. In practice I have found for example that 0.2 c.m. of water may be inserted in a 65 cigarette, without appreciably affecting its

burning qualities, and serves to efficiently treat the cigarette for the purposes set forth above. Cigarettes or the like are preferably treated just prior to the time at which they are to be smoked. After treating the cigarette in the manner above described, it is removed from the receptacle 2 and the needle 9, and is ready to be used.

70 It is to be understood that my invention is not to be limited merely to the treatment 75 of tobacco products, since it is likewise adapted to the treatment of cigars or cigarettes adapted to be used for medicinal purposes, and formed entirely or partly of substances other than tobacco. In such cases, 80 it is my intention to treat such articles with any desired substance.

It will be obvious to those skilled in the art, after understanding my invention, that other changes and modifications may be 85 made therein without departing from the spirit and scope of the invention, and I aim in the appended claims to cover such changes and modifications as are within the scope of 90 the invention.

What I claim as new and desire to secure 95 by Letters Patent is:

1. An article of manufacture comprising a reservoir for containing a treating substance, a plunger adapted to force said substance 95 from said reservoir, a receptacle portion adapted to receive and guide the end of a smokable roll of material, and a hollow perforating member of a length sufficient to be inserted a substantial distance into said roll 100 of material in communication with said reservoir and through which said substance is adapted to be injected into said roll of material.

2. An article of manufacture comprising a 105 reservoir for containing a treating substance and having a threaded portion, a plunger adapted to force said substance from said reservoir and having a threaded portion for engagement with the threaded portion of 110 said reservoir, whereby said plunger may be moved in said reservoir, a receptacle portion adapted to receive and guide the end of a smokable roll of material, and a hollow perforating member of a length sufficient to be 115 inserted a substantial distance into said roll of material in communication with said reservoir and through which said substance is adapted to be injected into said roll of material when said roll is placed in said receptacle portion.

3. An article of manufacture comprising a reservoir for containing a treating substance, a plunger adapted to force said substance from said reservoir, a detachable receptacle 125 portion adapted to receive and guide the end of a smokable roll of material, and a hollow perforating member of a length sufficient to be inserted a substantial distance into said roll of material in communication with said 130

reservoir and through which said substance is adapted to be injected into said roll of material.

4. An article of manufacture comprising
5 a receptacle portion adapted to receive and guide the end of a smokable roll of material, a hollow perforating member of a sufficient length to be inserted a substantial distance

into said roll of material when said roll is placed within said receptacle portion, and
10 means for holding a treating substance and for forcing said treating substance through said needle into said roll of material.

In testimony whereof I have signed my name to this specification.

ALAN W. C. MENZIES.
